UNITED STATES PATENT OFFICE.

SOLOMON S. SLAUGHAN, OF HOMESTEAD PARK, PENNSYLVANIA.

CHAIN GRATE.

1,382,686.

Specification of Letters Patent. Patented June 28, 1921.

Application filed April 20, 1920. Serial No. 375,256.

To all whom it may concern:

Be it known that I, SOLOMON S. SLAUGHAN, a citizen of the United States, residing at HOMESTEAD PARK, in the county of Allegheny and State of Pennsylvania, have invented certain new and useful Improvements in Chain Grates, of which the following is a specification.

This invention relates to grates of the 10 endless chain type, and the object thereof is to provide a grate of the class stated, in a manner as hereinafter set forth, comprising a plurality of links having interfitting connecting elements, thereby providing for 15 the complete assembly of the grate without the incorporation of any materials except those embodied in the link structures themselves.

Further objects of the invention are to 20 provide a device of the character described which is simple in its construction and arrangement, strong, durable and efficient in its use, and comparatively inexpensive to manufacture.

To the accomplishment of these and such other objects as may hereinafter appear, the invention consists of the novel construction, combination and arrangement of parts herein specifically described and illustrated in 30 the accompanying drawing wherein is shown an embodiment of the invention, but it is to be understood that changes, variations and modification may be restored to which come within the scope of the claims hereunto appended.

In the drawing forming a portion of this specification and wherein like numerals of reference designate corresponding parts throughout the several views:

40 Figure 1 is a top plan view of the chain grate in accordance with this invention.

Fig. 2 is a sectional view on line II-II, Fig. 1.

Fig. 3 is a perspective view of a link.

45 Fig. 4 is a longitudinal sectional view of associated links and their associated interfitting connecting elements.

Referring in detail to the drawing there is shown in Fig. 1 a pair of horizontally extending supporting bars 1 and 2, respectively, having my improved endless chain grate mounted therebetween.

The chain grate comprises a series of rows of links, each row consisting of a plurality

of links 3, and the links of one row being in 55 staggered relation with respect to the links of adjacent rows and having interfitting connection therewith.

The chain grate is mounted, in the fire box 4, on the supporting rollers 5, which 60 latter are suitably journaled in the supporting bars 1 and 2. The grate may be operated by any suitable drive mechanism and pass around suitable end rollers 6 journaled in the supporting bars 1 and 2 adjacent to 65 the front and rear ends of the latter.

Each of the links 3, comprising the chain grate, is preferably rectangular in contour and provided with rounded off lower corners 7 to facilitate its travel over the rolls 70 5 during its operation. The links 3 are formed with ribbed side faces 8 to provide for air passages when the chain grate is assembled.

Each link 3, adjacent one end thereof, is 75 formed with a duplex bearing aperture 9 gradually diminishing in diameter from the center 10 thereof toward its openings on respective sides of the link 3. Adjacent the other end of the link 3 are a pair of opposed trunnions 11 and 12, positioned on respective sides of the link, as clearly shown in Fig. 4 of the drawing. Each of the trunnions 11 and 12 is tapered to provide an 80 enlarged outer end 13.

Each of the trunnions 11 and 12 is of such 85 length as to extend nearly one-half way through the bearing aperture 9 of adjacent links in which it is pivotally seated.

While the enlarged end 13 of the trunnions 11 and 12 is necessarily of less diameter than the openings, at the sides of the links, of the bearing apertures 9 to permit the insertion of the former into the latter, the construction of the interfitting connection therebetween is such as to tend to prevent the lateral displacement of the links 90 relatively to each other. The proximity of the supporting bars 1 and 2 to adjacent rows of links also serves to lock the grate in the assembled position. In the said adjacent rows of links the trunnions on the sides of the links facing the bars are cut away to permit the said bars to be mounted closely to the links adjacent thereto.

105 It will be noted that in the assembly of the chain grate of my improved construction, no materials are required that are not

embodied in the link itself, thereby providing a simple, durable and inexpensive chain grate.

What I claim is:—

- 5 1. An endless chain grate comprising rows of links, each link of a row provided near one end with laterally projecting tapered trunnions larger in diameter at their outer than at their inner ends and near its other end with a transverse perforation gradually decreasing in diameter from its center toward each end thereof, the trunnions of one link extending into the perforations of a pair of links of adjacent rows 10 15 of links for connecting the links together.

2. An endless chain grate comprising

rows of links, the links of one row being staggered with respect to the links of an adjacent row, each of the links of a row provided with a pair of laterally disposed 20 tapered trunnions and a perforation gradually decreasing in diameter from its center toward each end thereof, said trunnions being larger in diameter at their outer than at their inner ends, and the trunnions of one 25 link having interfitting connection in the perforations of a pair of adjacent links whereby the rows of links are connected together and pivots are provided for the links during the travel thereof.

In testimony whereof I affix my signature.

SOLOMON S. SLAUGHAN.
